UNITED STATES PATENT OFFICE.

RAFAEL I. PARTIDA, OF TORREON, MEXICO.

AUTOMATIC RAILWAY-SWITCH DEVICE.

1,153,819.

Specification of Letters Patent. Patented Sept. 14, 1915.

Application filed February 19, 1913, Serial No. 749,344. Renewed March 4, 1915. Serial No. 12,109.

To all whom it may concern:

Be it known that I, RAFAEL IGNACIO PARTIDA, a citizen of the Republic of Mexico, and a resident of Torreon, Coahuila, Mexico, have invented a new and Improved 5 Automatic Railway-Switch Device, of which the following is a full, clear, and exact description.

My invention has for its objects to provide 10 improvements in automatic railway switch devices, such as shown in my Letters Patent, issued on December 13, 1910, under Number 978,639. In my improvements I provide arms, at the side of the track, which are operated by means of the weight of a car on track bars, these arms being secured to rock shafts, to which additional arms are secured, for raising above the ground trip members into position to be engaged by 15 members carried by a car, these trip members having slots in which flattened portions of rock shafts are disposed. The rock shafts are connected by gearing with means for moving a switch point.

Another object of the invention is to provide 20 a member for moving in a guideway on a car, the member having a pivoted arm for engaging the trip member when moved with the car in one direction, the arm being free to move in the said direction relatively to the member and the car, when the car is moved in the opposite direction.

Still other objects of the invention will appear in the following complete specification, in which the preferred form of the 25 invention is disclosed.

In the drawings similar characters of reference indicate corresponding parts in all the views, in which—

Figure 1 is a sectional view on the line 1—1 of Fig. 2; Fig. 2 is a sectional view on the line 2—2 of Fig. 1; Fig. 3 is a sectional view on the line 3—3 of Fig. 1; Fig. 4 is an enlarged fragmentary view showing 30 how the track member is adapted to raise the trip member; Fig. 5 is a sectional plan view of Fig. 4; Fig. 6 is a sectional view on the line 6—6 of Fig. 7, showing the slide through which the trip member is adapted 35 to move; Fig. 7 is a sectional view on the line 7—7 of Fig. 6; and Fig. 8 is an enlarged front elevation showing one of the trip operating members.

By referring to the drawings it will be

seen that tracks 5 are provided, and that 55 the switch point 6, which is pivoted at 7, is adapted to move relatively to these tracks 5, in the customary manner, the following means being provided for so moving the 60 switch point 6.

Journaled in a frame 8, disposed below the horizontal plane at the top 9 of the street or road, there are rock shafts 10, which have beveled gears 11, at their inner ends, which mesh with a beveled gear 12 65 on the plate 13, which is adapted to rotate on its central pivot 14, disposed at 15 in the frame 8. Two of these shafts 10 are provided, one being disposed at each side as shown in Fig. 3 of the drawings, and 70 each of the shafts having a beveled gear 11, meshing with the bevel gear 12, on the rotatable plate 13. As a means for rotating these rock shafts 10, I provide trip members 16 one for each of the rock shafts 10, 75 as will be seen by referring to the drawings. These trip members 16 have slots 17, in which are disposed the flattened portions 18 of the rock shafts 10. It will therefore be seen that when one of the rock shafts 80 10 is disposed as shown in Fig. 7 of the drawings, with the slots 17 of the trip members 16 in vertical position, the trip members 16 may be raised through the opening 19 in the slide 20, which is provided for 85 covering the opening 21 in the top 22 of the frame 8.

The trip members 16 are raised by means of the curved terminals 23 of the arms 24, these arms 24 being secured to the rock 90 shafts 25. The rock shafts 25 are journaled in bearings in the standards 26, and also in bearings in the sides 27 of the frame 9. To the shafts 25 are secured additional arms 28, which are disposed under the ends 29 95 of the track members 30, so that when the car wheels 31 press down on these track members 30 against the resiliency of the springs 32, the shoulders 33 on the track members 30 will engage and depress the 100 arms 28 to rock the shafts 25, and raise the arms 24, which will, as has been stated, raise the trip members 16.

When the trip members 16 have been raised as has been stated, they are in a position 105 to be engaged by the operating members 34, pivoted at 35, to the brackets 36, secured to the member 37, which slides in

guideways 38, at the front and rear of the car. As will best be seen by referring to Fig. 8 of the drawings, the trip operating members 34 have laterally extending portions 34^a, so that they will be adapted to engage the trip members 16, even though the car should be moved slightly laterally relatively to the trip members.

I prefer to construct my device so that the 10 flattened portions 18 of the shafts 10 will hold the trip members at an angle to each other, and so that the trip members will normally be disposed relatively to each other in the position shown in Fig. 4 of the 15 drawings. It will be understood that with the arrangement of the beveled gears 11 and 12, when one of the trip members 16 is moved downward, rotating the rock shaft 10, on which it is mounted, the other trip 20 member 16 will be moved to a vertical position.

To the rotatable plate 13, there is secured a lug 39, which is engaged by the arms 40 on the lever 41, this lever 41 being connected by a link 42 with a second lever 43, the second lever 43 having an arm 44, disposed between the contact members 45, secured to the shanks 46, these shanks 46 passing through orifices in the brackets 47, 30 and being held extending inwardly from the brackets 47 by means of the springs 48. The brackets 47 are secured to the shifting bar 49, which is adapted to move in guide members 50, to throw the switch point 6, to 35 which it is articulated at 51.

The members 37 are held yieldingly upward on the car 52, by means of the springs 53, which are disposed to the car platform 52^a, and also to the members 37, shanks 54 40 being also secured to the members 37 passing to the car platform, so that the shanks 54, with the members 37, may be pressed by means of the foot plates 55, at the top of the shanks 54.

45 When a car 52 is moved along the track so that the wheels rest on the track members 30, the trips 16 will be raised in the manner which has been described, so that one of the members 37 is depressed by means of the foot plate 55. The trip operating member 34, pivoted to the said member 37, will be disposed in position for engaging the trip member 16, which is disposed at the same side of the car, and as the car moves 50 along the track, the said trip member 16 will be moved to rotate the shaft 10, with which it has a sliding engagement. With the rotation of this shaft 10, the plate 13 will be rotated, and by the means described, 55 the switch point 6 will be moved relatively to the point. At the same time the shaft 10 at the other side of the track will be rotated by means of its beveled gear 11, to raise the trip member 16 at the other 60 side of the track.

Having thus described my invention, I claim as new and desire to secure by Letters Patent:

1. In an automatic railway switch device, a track, a switch point movable relatively to the track, a member mounted to rotate on a vertical axis, means by which the member is adapted to move the switch point, a shaft, gearing connecting the shaft with a member for rotating the latter, a trip member having sliding engagement with the shaft for rotating the latter, a track member, and means operable by the movement of the track member for moving the trip member relatively to the shaft. 70

2. In an automatic railway switch device, a track, a switch point movable relatively to the track, a shaft having a flattened portion, a trip member having a slot in which the flattened portion of the shaft is disposed, means by which the rotation of the shaft will move the switch point, a track member, and means operable by the movement of the track member for moving the trip member relatively to the shaft. 80

3. In an automatic railway switch device, a track, a switch point movable relatively to the track, a transverse shaft, means by which the rotation of the shaft will move the switch point, a trip member for rotating the shaft, and free to move in one direction relatively to the shaft, a track member, and means by which the track member is adapted to move the trip member relatively to the shaft. 90

4. In an automatic railway switch device, a track, a switch point movable relatively to the track, a transverse shaft, means by which the rotation of the shaft will move the switch point, a trip member having a slot in which an angular portion of the shaft is disposed, a track member, a second shaft, an arm secured to the second shaft for moving the trip member relatively to the first shaft and a second arm on the second shaft 100 adapted to be operated by the track member.

5. In an automatic railway switch device, a track, a switch point movable relatively to the track, a member mounted to rotate, means by which the member is adapted to move the switch point, a shaft, gearing connecting the shaft with the member for rotating the latter, a trip member having sliding engagement with the shaft for rotating the latter, a track member, a second shaft, an arm secured to the second shaft for moving the trip member, and a second arm secured to the shaft, and adapted to be operated by the track member. 115

6. In an automatic railway switch device, a track, a switch point for moving relatively to the track, a guideway having an opening at its top, a horizontal slide for moving in the guideway for closing the opening in the guideway, the slide having an opening, 125 130

5 a trip member for moving up through the slot, and for moving with the slide longitudinally of the guideway, means operable by the said longitudinal movement of the trip member for moving the switch point, a track member for moving relatively to the track, and means by which the track member is adapted to raise the trip member through the slot.

10 7. In an automatic railway switch device, a track, a switch point for moving relatively to the track, a guideway, a horizontal slide for moving in the guideway and having an opening, a member mounted to rotate, means by which the member is adapted to move the switch point, a shaft, gearing connecting the shaft with the member, a trip member hav-

ing a sliding engagement with the shaft for rotating the latter, the trip member being adapted to move up through the guideway 20 and for moving with the rotation of the shaft longitudinally of the guideway, a track member for moving relatively to the track, and means by which the track is adapted to raise the trip member through 25 the guideway.

In testimony whereof I have signed my name to this specification in the presence of two subscribing witnesses.

RAFAEL I. PARTIDA.
